WINDOW CONSTRUCTION AND REGULATOR
FOR SAME

Albert W. Susor, Toledo, Ohio

Application June 20, 1936, Serial No. 86,264

5 Claims. (Cl. 296—44)

This application relates to window constructions and to regulators for the same.

The principal object of the present invention is to provide a window construction particularly suitable for automobile doors, the same comprising two co-planar windows covering the window opening of the door, with the windows so constructed as to rotate in their own planes about a common pivot. The regulator for these windows is so constructed that it rotates the windows sequentially and not simultaneously. On opening, the regulator will first rotate open the leading one of the two windows and finally will rotate open the trailing one of the two windows; on closing the reverse action will take place. Inasmuch as the leading edge of the leading window may be moved slightly, without opening the trailing window, it is practical to use this construction as a substitute for the presently known ventilating-type constructions where single windows having compound movements are provided.

The present invention also relates to a regulator for two adjacent co-planar windows or the like, the regulator being so constructed as to move the windows sequentially and not simultaneously.

Further objects will presently be understood upon reference to the appended drawings. In these drawings,

Fig. 1 shows a door with both windows in full closed position, regulator parts being shown in place;

Fig. 2 shows the door with the leading window open slightly;

Figs. 2a and 2b show the regulator parts in full open and full closed positions;

Fig. 3 shows the door with the leading window open completely;

Fig. 4 is a section on line 4—4 of Fig. 1;

Fig. 5 is a detail of the bottom edge channels and the pivot mountings for the windows;

Fig. 6 is a detail of a supplementary guide;

Fig. 7 shows another modification with the regulator parts in window closed position;

Fig. 7a is a section on line 7a—7a of Fig. 7.

Referring to the drawings, it will be seen that Fig. 1 discloses an automobile door 10 having a window opening bounded by the lines 11 and adapted to be covered by two separate windows 12 and 14.

The window 12 has its lower edge provided with a channel 15 terminating in a bar 16 through which passes a pivot pin 17 at the leading edge of the door and mounted on the door so that the window 12 may rotate in its own plane on an axis transverse to and substantially at the cor-

ner of the window 12, and for this reason the window 12 is more or less sector-shaped, with its trailing edge having a felt-lined channel 18 formed on an arc centered on pivot 17 and receiving the complementarily shaped leading edge 19 of the window 14. In closed position the leading edge of the window 12 is adjacent the leading edge of the door and the leading part of the opening 11 is closed by the window 12. In full open position, the leading edge of window 12 occupies a horizontal position below the lower horizontal edge of the opening 11, and movement of the window 12 from its closed position to its full open position is provided by rotation of window 12 about its pivot 17.

The trailing window 14 has its lower edge provided with a channel 20 terminating in a bar 21 through which passes pivot pin 17 and it is thus mounted to swing about the pivot 17 and in its own plane, and since the leading edge 19 of this window is received within the channel 18, and the trailing edge is received within an arcuate channel at the trailing edge of the door opening 11, the trailing window will also be guided in its movement.

To supplement the guiding provided by the guiding channel 18 between the trailing edge of the leading window 12 and the leading edge of the trailing window 14, there is provided on the channel 20 at the lower edge of the trailing window 14 a guiding element 22 adapted to fit within the channel 18 as soon as the leading window starts to swing out of its closed position, the guiding element operating to guide the adjacent edges of the windows even after the channel 18 has left the leading edge of the trailing window.

For rotating these windows about the pivot 17, the channels 15—20 receive buttons on the free ends 23—24 of swinging arms 25—26 fixed to and rotatable with the pinions 27—28 of a regulator having an operating pinion 29 rotatable by rotation applied to the shaft 30 of the pinion through some manually operable handle or crank 31 or the like. The pinions 27, 28, and 29 are not gear-cut on their entire peripheries but are in the nature of segmental gears only, with the arrangement such that the first part of the rotation of the pinion 29 in the counterclockwise direction indicated in Fig. 1 will rotate the pinion 27 clockwise but will not rotate the pinion 28; when pinion 27 has been rotated to its complete extent, further rotation of pinion 29 will no longer cause rotation of pinion 27 but will start the rotation of pinion 28 clockwise, and continued rotation of pinion 29 from this point will rotate pinion 28.

to its full extent. This arrangement provides sequential operation of the two windows 12 and 14. For opening, window 12 must first be open to its complete extent before window 14 can be opened; for closing, window 14 must be closed to its complete extent before window 12 will start closing.

If desired, the guiding channel 18, instead of being carried by and movable with the window 12, may be formed as part of the door, as indicated at 18a in Fig. 7. In this figure, the opening covered by the windows is a double opening with the two parts thereof separated by the door frame portion 18a which on its opposite edges is provided with channels receiving the adjacent edges of the windows 12 and 14. Because the adjacent edges of the windows are guided by the fixed channel 18a, the provision of the pivotal mounting for the trailing window 14, and the provision of the supplementary guide 22, will not be necessary; in other respects, however, the construction of Fig. 7 is like that of Fig. 1.

I claim:

1. Window construction comprising a wall having a window opening, two co-planar windows covering said opening, one of said windows being pivoted at that lower corner thereof more remote from the other window than is the other lower corner thereof to rotate about said corner and in its own plane, means mounting the other window so that it also may pivot about the aforesaid pivoting corner of the first mentioned window, means to rotate the first mentioned window and rotate the second mentioned window about their common pivot, and means guiding the adjacent edges of the two windows.

2. Window construction comprising a wall having a window opening, two co-planar windows covering said opening, one of said windows being pivoted at that lower corner thereof more remote from the other window than is the other lower corner thereof to rotate about said corner and in its own plane, means mounting the other window so that it also may pivot about the aforesaid pivoting corner of the first mentioned window, means to rotate the first mentioned window and rotate the second mentioned window about their common pivot, and common

means guiding the adjacent edges of the two windows.

3. Window construction comprising a wall having a window opening, two co-planar windows covering said opening, one of said windows being pivoted at that lower corner thereof more remote from the other window than is the other lower corner thereof to rotate about said corner and in its own plane, means mounting the other window so that it also may pivot about the aforesaid pivoting corner of the first mentioned window, means to rotate the first mentioned window and rotate the second mentioned window about their common pivot, the operating means for the two windows being interlocked to operate sequentially and not simultaneously. 5

4. Window construction comprising a wall having a window opening, two co-planar windows covering said opening, one of said windows being pivoted at that lower corner thereof more remote from the other window than is the other lower corner thereof to rotate about said corner and in its own plane, means mounting the other window so that it also may pivot about the aforesaid pivoting corner of the first 10 mentioned window, means to rotate the first mentioned window and rotate the second mentioned window about their common pivot, 20 and means guiding the adjacent edges of the two windows, the operating means for the two windows being interlocked to operate sequentially and not simultaneously. 25

5. Window construction comprising a wall having a window opening, two co-planar windows covering said opening, one of said windows being pivoted at that lower corner thereof more remote from the other window than is the other lower corner thereof to rotate about said corner and in its own plane, means mounting the other window so that it also may pivot about the aforesaid pivoting corner of the first mentioned window, means to rotate the first mentioned window and rotate the second mentioned window about their common pivot, and common 30 means guiding the adjacent edges of the two windows, the operating means for the two windows being interlocked to operate sequentially and not simultaneously. 35 40 45
